UNITED STATES PATENT OFFICE.

CHARLES PEARSON, OF CHICAGO, ILLINOIS, ASSIGNOR TO INTERNATIONAL HARVESTER COMPANY, OF CHICAGO, ILLINOIS, A CORPORATION OF NEW JERSEY.

STACKER.

Application filed May 16, 1923. Serial No. 639,243.

My invention relates to improvements in material handling devices of the type designed to lift and deliver hay, or similar loose or bulky materials, to an elevated point, 5 as in building a stack. It has particularly to do with extensible stackers of the over-shot type and the primary object of the invention is to reduce the amount of power required to operate a stacker, especially at the 10 beginning of the lift, and to provide improved mechanism for regulating and operating the extensible head of the stacker so that it will have a wide range of adjustment, give a high lift when required and operate smoothly and without binding or strain.

A further object is to provide simple means for cushioning the lifting frame both at the end of the lift and at the end of 20 the return or drop.

The main objects stated, as well as minor ones that will become apparent as the description proceeds, are attained by providing a structure having improved lever 25 mechanism for hoisting and lowering the stacker head and for controlling the degree of extension and retraction automatically given it at each operation of the stacker and also novel and simple cushioning mechanism 30 in which a spring which is bodily movable with the lifting frame is made to perform several functions by being put under tension, through shifting of its points of attachment, at termination of the upward and 35 downward swings of the lifting frame, whereby it is made to cushion the frame at each end of its movement, assist in raising the frame at the beginning of the lift, when the strain is greatest, and initiate the return 40 movement of the lifting frame. The invention accordingly resides in the organization and details of construction, or equivalents thereof, hereinafter described and claimed.

45 In the drawings—

Fig. 1 is a plan view of a stacker embodying my invention;

Fig. 2 is a side view with the stacker in lowered position;

50 Fig. 3 is a similar view showing the stacker raised;

Fig. 4 is an enlarged detail view showing the links and spring connecting the main and secondary lifting arms;

55 Fig. 5 is an enlarged detail view of the

coupling between the lift controlling slide and link;

Fig. 6 is a detail view on line 6—6 of Fig. 2 showing the pivot connection of a 60 lifting rod;

Fig. 7 is a side view on an enlarged scale of the parts comprising the elevating connections, with the relative positions of the parts at intermediate stage of elevation indicated in dotted lines;

Fig. 8 is an enlarged detail view on line 8—8 of Fig. 7;

Fig. 9 is a similar view on line 9—9 of Fig. 7;

Fig. 10 is a side view as in Fig. 3 but with 70 the extension set for extreme height; and

Fig. 11 is an enlarged detail view of the central portion of Fig. 10 omitting the outer bar of the connecting link to show the spring connection.

My improved stacker comprises a base composed of parallel side sills 20 and 21 connected at front and rear at an intermediate point by cross pieces 22. The front of this base frame is preferably supported 80 on an axle and wheels 23 carried on journal brackets 23^a and the axle may be cranked as shown and made vertically adjustable in any suitable manner. At the rear, the base frame has a rigid vertical 85 portion which may be composed of three vertical posts 24, one at each corner of the frame and one midway between, which are secured to the side sills and rear cross piece. These posts are connected at the top by 90 transverse member 25 and are suitably braced as by the diagonal side members 26 and diverging rods 27. At points towards the rear of the sills 20 and 21, there are secured short vertical standards 28 to which 95 are pivoted the main lifting arms 29 of the vertically swinging lifting frame. These arms are located directly above the sills, the front ends of which are beveled off as at 30 to permit the outer ends of the lifting arms, when they rest thereon, to come near the ground. Slidable extension arms 31 are mounted on the main lifting arms 29 on which they are guided and held in position by a yoke piece 32 (Fig. 6) secured to the front ends of the main arms and by guide brackets 33 (Fig. 9) secured on the rear ends of the extension arms 31 and extending below the main arms 29 where they carry rollers 34 which travel on the lower 100

edges of arms 29. These extension arms carry the stacker head 35 which may be of any usual or preferred construction. Secondary lifting or radius arms 36 are pivoted on the upper ends of the corner posts 24 and extend toward the main lifting arms, their point of connection to the base frame being forward of the lifting arms, as shown in the drawings, and links 37 each composed of a pair of spaced parallel bars pivoted on opposite sides of the ends of the arms 36 and to the main arms 29 toward their outer ends, as best seen in Figs. 1, 4 and 8, serve to pivotally connect the main and secondary lifting arms. As the radius arms 36 are pivoted at the top of posts 24 the connecting point of the links 37 to arms 36 is more distant from the base frame than is the connecting point between the links 37 and the main arms 29, the links 37 swinging through an arc of substantially 180 degrees as the lifting frame operates, and by reason of the arrangement of pivotal points stated, links 37 act as stops for the lifting frame when the limit of their upward swing is reached, as in Fig. 10. The movement of links 37 is also made use of in connection with resilient means hereinafter described, for modifying the movement of the lifting frame. To reduce friction, the pivots for links 37 preferably include bearing sleeves having spacing collars 37^a (Fig. 8). Lifting arms 29 and 36 together with the connecting links 37 afford a construction which becomes rigid when the secondary arms 36 reach a substantially vertical position, that is, further swing of the lifting frame toward the stack is automatically stopped by the links 37 when the parts reach the positions seen in Figs. 3 and 10. Need of a buffer frame is therefore eliminated. The secondary arms 36 control the lift of the extension arms 31 and are connected to the extension arms by an adjustable coupling comprising slidable sleeves 38, movable on arms 36, which are connected by flexible linkage, such as rods 39 and chain links 40 (Fig. 5), to upwardly projecting arms of the brackets 33 on arms 31. The arms 36 are provided with means for controlling the extent of movement of sleeves 38 consisting, for instance, of a series of spaced apertures 41 and stop pins 42 which are adapted for insertion in any of the apertures to limit movement of sleeves 38 on the secondary lifting arms 36. In connection with the parallel bars composing the links 37, which connect the main and secondary lifting arms, there is provided a spring tension device composed of contractile springs 43 positioned between the bars of links 37 and attached thereto at their upper ends by a pivoted staple 43^a while their opposite ends are attached to short rods 44 pivoted on bracket members 45 secured to the main lift-

ing arms 29 and extending above the extension arms 31, as shown in detail in Figs. 7 and 8, the pivot point of rods 44 being just above that of links 37. As means for applying power to raise and lower the lifting arms, there is provided a vertically swinging jib composed of upwardly converging beams 46 which are pivoted on the side sills at their lower ends and rigidly connected near their upper ends as by cross piece 47. The members 46 of the jib have their outer ends connected to the ends of the main lifting arms 29 by means of lifting rods 48 which are pivoted to the ends of the jib members and to the lifting arms, the pivotal connection to the lifting arms being preferably formed by journaling the outwardly bent ends of the lifting rods in openings through arms 29 and the members of yoke 32, as clearly shown in Fig. 6. Between the ends of the jib members 46, there is journaled a sheave or pulley 49 on each side of which are pivoted the arms of a U-shaped clevis member 50. Twin sheaves 51 are journaled centrally of the transverse bar 25 of the rear end of the base frame and another sheave 52 is mounted immediately below these on the base of the frame. An operating cable 53 is attached to the clevis 50 on the end of the jib and extends over one of the sheaves 51, around sheave 49 on the end of the jib, then over the second sheave 51, and finally under sheave 52 from which it extends to the source of power.

The operation of the stacker is effected through the cable 53 in the usual way, the lifting elements in my novel organization functioning in the following manner:—when the device is in lowered position, as in Fig. 2, the relation of parts is such that springs 43 are under tension and are positioned so that they exert a lifting action on arms 29. If cable 53 is now pulled, the jib will begin its swing and lifting rods 48 will pull upward on lifting arms 29 and the assistance of springs 43 will cause lifting movement to start without strain and with application of less power to the cable than heretofore required in old constructions. As lifting progresses and the parts reach the intermediate positions shown in dotted lines on Fig. 7, the springs 43 become slack and as the main and secondary arms rise, the links 37 connecting them swing in such a way that the upper ends of springs 43, which are connected thereto, are shifted from one side of their points of connection to arms 29 to the other side thereof and as the end of the raising movement is reached, the springs are again placed under tension, as shown in Fig. 3, and the end of the upward swing is cushioned in a manner to give the load carried by the head 35 a pitching impulse, the tension of springs 43 then causing the lifting arms, which have passed dead center, to re-

coil, thereby starting the downward movement which continues as cable 53 is released. At the end of the downward movement of the lifting arms, the springs 43 again come under tension and act to break the jar of the frame as it hits the ground. During the lifting operation just described, it is assumed that pins 42 were in the lower openings 41 in arms 36 and that the sleeves 38 were free to slide on said arms. Under these conditions, the sleeves moved down the arms as the lift progressed and there was no extension of arms 31 and no additional lift given the stacker head. If it is desired to increase the lift, the pins 42 are placed in the last opening 41, for instance, so that sleeves 38 can have no sliding movement, consequently they will transmit a pull through the flexible couplings 39 and 40, as the lift progresses, to the inner ends of the extension arms 31 and these will accordingly slide outwardly on the main lifting arms 29 and finally assume the position illustrated in Fig. 10. It will be evident that the degree of extension given the arms 31 will be governed by the position of stop pins 42 on arms 36, and that the height of lift can be gradually stepped up to follow a rising stack.

It will be clear from the above description that I have devised an improved construction that is simple, strong and easily operated and in which the height of lift can be quickly and easily adjusted within a considerable range, and that the novel features of construction above described are capable of considerable variation within the scope of the following claims.

I claim as my invention:

1. The combination of a base frame, a lifting frame pivoted thereon to swing vertically through a predetermined arc, means for swinging the lifting frame, a spring carried on said lifting frame and bodily movable therewith, and means actuated by movement of said frame for putting the spring under tension at both ends of the arc of movement of the frame.

2. The combination of a base frame, a lifting frame pivoted thereon to swing vertically through a predetermined arc, means for swinging the lifting frame, a spring with one end connected to said frame and its other end connected to a point of support shiftable with respect to said lifting frame, and means actuated by movement of said frame for shifting said support and reversing the action of the spring at each end of the arc of movement of the frame.

3. The combination of a base frame, a lifting frame pivoted thereon to swing vertically through a predetermined arc, means for swinging the lifting frame, a contractile spring with one end connected to said lifting frame and its other end connected to a

link pivotally mounted on the lifting frame at a point eccentric to the point of connection of the spring thereto, and means actuated by movement of said frame for swinging the link on its pivot and shifting the spring from one side of its connection to the frame to the other.

4. The combination of a base frame, a lifting frame pivoted thereon to swing vertically through a predetermined arc, means for swinging the lifting frame, a contractile spring with one end connected to said lifting frame and its other end connected to a link having one end pivoted to the lifting frame at a point eccentric to the point of connection of the spring thereto, an arm pivoted on the base frame to swing in the same direction as the lifting frame, and a pivotal connection between said arm and the other end of said link.

5. The combination of a base frame, a lifting frame pivoted thereon comprising a main lifting arm and an extension arm slidably mounted thereon, means for swinging the lifting frame, a secondary lifting arm pivoted on the base frame to swing in the same direction as the lifting frame, a link pivotally connecting said secondary arm with the main lifting arm, and a flexible coupling between said secondary arm and the extension arm.

6. The combination of a base frame, a lifting frame pivoted thereon comprising a main lifting arm and an extension arm slidably mounted thereon, means for swinging the lifting frame, a secondary lifting arm pivoted on the base frame to swing in the same direction as the lifting frame, a link pivotally connecting said secondary arm with the main lifting arm, a flexible coupling between said secondary arm and the extension arm, and means permitting said coupling to have movement longitudinally of one of said arms.

7. The combination of a base frame, a lifting frame pivoted thereon comprising a main lifting arm and an extension arm slidably mounted thereon, means for swinging the lifting frame, a secondary lifting arm pivoted on the base frame to swing in the same direction as the lifting frame, a link pivotally connecting said secondary arm with the main lifting arm, a flexible coupling between said secondary arm and the extension arm including a slidable member mounted on said secondary arm, and means for regulating the extent of movement of the slidable member on said arm.

8. The combination of a base frame, a lifting frame pivoted thereon to swing vertically, and means for limiting the arc of movement of the lifting frame comprising an arm pivoted on the base frame to swing with the lifting frame and a link pivotally connecting said arm and lifting frame, the

connection of the link to the lifting frame being nearer the base than the connection of the link to the arm.

9. The combination of a base frame, a lifting frame pivoted thereon to swing vertically, a radius arm pivoted on the base frame to swing with the lifting frame and spaced therefrom, a link pivoted to the end of said radius arm and pivoted to the lifting frame at a point nearer the base frame than

the end of said radius arm, whereby said link is swung from one side to the other of its pivot to the lifting frame at each actuation thereof and the limit of movement in one direction between said link and its connections is reached when the lifting frame is at the end of its upward swing. 15

In testimony whereof I affix my signature.

CHARLES PEARSON.
